INVENTOR

THOMAS F. CÔTÉ

By

Frank Murphy Jr.

ATTORNEY.

UNITED STATES PATENT OFFICE.

THOMAS F. CÔTÉ, OF PRINCE ALBERT, SASKATCHEWAN, CANADA.

FUSE PLUG.

1,424,714.

Specification of Letters Patent. Patented Aug. 1, 1922.

Application filed September 21, 1920. Serial No. 411,880.

To all whom it may concern:

Be it known that I, THOMAS F. CÔTÉ, a subject of the King of Great Britain, residing at Prince Albert, in the Province of Saskatchewan and Dominion of Canada, have invented certain new and useful Improvements in Fuse Plugs; and I do hereby declare the following to be a full, clear, and exact description of the invention, such as 10 will enable others skilled in the art to which it appertains to make and use the same.

This invention relates to new and useful improvements in renewable fuse plugs and has for its primary object the provision of 15 a device of the above stated character wherein a burnt or destroyed fuse element may be quickly and easily removed and another substituted therefor so as to place the plug in condition for further use.

20 Another object of this invention is the provision of means for securing the ends of the fuse elements to the contacts of the plug which will prevent corroding or fusing of said contacts to the ends of the fuse elements 25 when the latter are blown out or destroyed.

A further object of this invention is the provision of means for permitting the fumes or gases within the plug to escape when the fuse element blows out or is fused.

30 A still further object of this invention is the provision of a fuse plug of the above stated character which will be simple, durable and efficient, and which may be manufactured and sold at a comparatively low 35 cost.

With these and other objects in view as will become more apparent as the description proceeds, the invention consists in certain novel features of construction, combination, and arrangement of parts as will be hereinafter more fully described and claimed.

40 For a complete understanding of my invention, reference is to be had to the following description and accompanying drawings, 45 in which:—

Figure 1 is a vertical sectional view illustrating a fuse plug constructed in accordance with my invention,

Figure 2 is an enlarged sectional view illustrating the cover for the body of the fuse plug,

Figure 3 is a detail view illustrating the fuse element,

Figure 4 is an enlarged sectional view illustrating the insulating sleeve,

Figure 5 is an enlarged detail view of a closure cap or shell.

Referring in detail to the drawings, the numeral 1 indicates the body of the fuse plug and is constructed from porcelain or any other material suitable for the purpose and which is of an insulating nature, and the body 1 has formed upon its outer face 60 pressed screw threads 2 that terminate short of one end of said body so that the last named 65 end of the body will form a finger grip 3 for threading the body into and out of a shell 4. The end of the body which has the finger grip 3 is closed and provided with an opening 5 in which is secured a contact 6. 70 The contact 6 is provided with a flange 7 that abuts the closed end of the body while the contact extends upwardly into the body and has a substantially oval shaped end 8. The shell 4 is constructed from metal or 75 any other material suitable for the purpose and has screw threads 9 pressed in the same for cooperation with the screw threads 2 of the body 1 so that said body can be readily threaded into the shell and be firmly 80 held therein. A cover 10 of insulating material is secured to the closed end of the shell 4 and is provided with a vent opening 11. The closed end of the shell 4 is also provided with a vent opening that aligns with the 85 vent opening 11 so that the fumes within the body may readily escape to the atmosphere on the fusing of the fuse element.

A sleeve 12 of insulating material has each end open and receives a fuse element 13. 90 The fuse element 13 has cut-out portions 14 adjacent each end and the fuse element is bent at the cut-out portions to overlie the ends of the sleeve 12 and in opposite directions as clearly shown in the drawings. 95 Closure caps 15 are adapted to seal the ends of the sleeve 12 and also retain the right angled ends of the fuse elements in engagement with the ends of the sleeve. The closure caps 15 are of hollow formation and one of said closure caps is adapted to receive the substantially oval-shaped end of the contact 6 while the other closure cap engages the closed end of the shell 4. The sleeve 12 is provided with vent openings 16 100 at a point intermediate its ends and which are adapted to permit the fumes or gases caused by the fusing of the fuse elements to escape from said sleeves into the body 1 whence they may escape from the body to 110

the atmosphere by way of the vent opening 11.

- From the foregoing description taken in connection with the accompanying drawings it will be noted that a fuse plug has been provided wherein the fuse element may be readily and quickly removed when fused by detaching the shell 4 from the body and removing the sleeve 12 from the body.
- 10 After the removal of the sleeve 12 from the body, the closure caps 15 are removed freeing the ends of the destroyed fuse elements and permitting a fuse element to be substituted in lieu of the one destroyed. It is also to be noted that the fumes or gases may readily escape from the plug without any danger of flame escaping from the plug during the fusing of the fuse element.
- The vent opening 11 in the cover 10 is surrounded by a recess 17 in which is positioned a disk 18 constructed of comparatively thin paper or similar material and on which is adapted to be printed the amperage of the fuse plug. This disk is adapted to prevent foreign matter from entering the interior of the body by way of the vent opening 11 and on the fusing of the fuse element, the cap will be destroyed or blown off indicating that the fuse element has been destroyed or fused.

While I have shown and described the preferred embodiment of my invention, it will be understood that minor changes in construction, combination, and arrangement of parts may be made without departing from the spirit and scope of the invention as claimed.

Having thus described my invention what I claim is:—

- 10 1. A fuse plug comprising a body having one end open and its other end closed, a shell closing the open end of said body, a contact secured in the closed end of said body and

having a reduced inner end, an insulating sleeve in said body and spaced from the 45 walls thereof and having each end open, a fuse element having cut away portions at each end and having its ends bent at right angles in opposite directions to engage the ends of the sleeve and said fuse elements 50 passing diagonally through the sleeve, closure caps closing the ends of the sleeve and securing the ends of the fuse element to the sleeve and one of said closure caps receiving the reduced end of the contact and the 55 other closure cap engaging the shell, said sleeve having vent openings at a point intermediate its ends.

2. A fuse plug comprising a body, a metallic shell secured to said body and having 60 a vent opening, a contact carried by said body, a closure cap for said shell and having a vent opening, a fuse element connecting the contact and shell, said second named vent opening being surrounded by a recess, 65 and a destructible disk located within said recess and closing the vent openings and adapted to bear the amperage of the fuse plug.

3. A fuse plug comprising a body, a shell 70 for said body, a contact projecting into the body, an insulating sleeve in said body, a fuse element in said sleeve and having its ends disposed against the ends of the sleeve, and cup-shaped caps in the ends of the 75 sleeve and having marginal flanges adapted to bind the ends of the fuse element against the sleeve, one of said caps engaging the shell and the other cap receiving a portion of the contact.

In testimony whereof I affix my signature in presence of two witnesses.

THOMAS F. CÔTE.
